ATTORNEY

UNITED STATES PATENT OFFICE

GEORGE ALBERT LYON, OF PHILADELPHIA, PENNSYLVANIA, ASSIGNOR, BY MESNE ASSIGNMENTS, TO AMERICAN CHAIN COMPANY, INC., A CORPORATION OF NEW YORK

VEHICLE BUFFER DEVICE

Application filed July 12, 1923. Serial No. 651,038.

This invention relates to buffer or bumper devices for automobiles in which the buffer front strips are formed with bent or folded end connector portions adapted to be directly bolted to each other at the ends of the buffer front and also to be simultaneously bolted in some cases to the ends of the buffer supporting members or strips; or, if desired, these connector portions may be curved or bent at their ends so as to be brought into edge engagement with each other and then bolted or clamped to a separate connector plate, casting or block, which may be interposed between their adjacent portions for this purpose.

In the accompanying drawing showing in a somewhat diagrammatic way a number of illustrative embodiments of this invention—

Fig. 1 is a front view of an illustrative buffer.

Fig. 2 is a plan view thereof.

Fig. 3 is an enlarged detail perspective view showing the end connection used in this buffer.

Fig. 4 is an enlarged detail showing another form of end connection, and

Fig. 5 is a side sectional view thereof.

Fig. 6 is a rear view of another form of illustrative buffer.

Fig. 7 is a top view thereof.

In the illustrative form of buffer shown in Figs. 1, 2 and 3 the buffer front may, if desired, be formed of two strips of tempered spring steel of about one and one-half to two and a half inches wide and a quarter to three-eighths of an inch thick, more or less, which may be arranged in vertically spaced position with their adjacent edges one to three inches apart or so and connected at several points along the buffer front by suitable clamps or connecting devices 30, which may also serve to connect to these front strips or members the ends 19, 24 of the buffer supporting or attaching member or strip. This attaching member may have a laterally extending or brace bar portion 21 spaced considerably to

the rear of the buffer front as shown in Fig. 2 and having at each end the resilient bent portions 20, 22, so as to yieldingly support the inturned connecting ends 19, 24 which may be apertured to receive the connecting bolts 50 17 of the clamping members 30. In this way the connecting ends 19, 24 may be brought into direct engagement with both the buffer front strips 25, 26, if desired, so as to directly support them and hold them in substantial vertical alignment. The outer ends of these buffer front strips may be rearwardly bent or folded as shown in Fig. 2 and may have specially shaped bent connector portions 7, 9 which may be rearwardly bent and also bent 60 toward each other so that their meeting edges 79 may be brought into substantial alignment with each other as shown in Fig. 3 to form a neat finish at this point of the buffer. These end connector portions of the strips may be clamped or connected in any suitable way and it is convenient to bolt these parts of the strips to a separate connector plate or member such as 41 which may be stamped into shape to fit within the ends of these cooperating strips 70 where it may be securely and removably fastened as by the round headed bolts 40 extending through the strip ends and the nuts 42 screwed against the connector plate to the rear.

Fig. 4 shows another form of desirable connection for such buffer front strips by which the two cooperating front strips 43, 44 may be securely connected in vertically separated vertically aligned position, if desired. For 80 this purpose diagonal folds or bends along the lines 47, 49 may be made in these strips so that the end connector portions 34 are formed integral with the two front strips which are then bent forward into parallel 85 position to form the laterally extending contact portions 45, 46 which may be securely bolted together by one or more bolts such as 47 passing through holes in these strips and tightly holding them together as by the nuts 90

48 under which lock washers may be provided, if desired. If desired in some cases a suitable buffer supporting member may have its ends clamped or bolted to these co-operating connector portions 34 and as shown 5 in Figs. 4 and 5, such a supporting member 31 may be formed with rounded ends 32 preferably arranged closely behind or in front of these connector portions 34 and secured thereto as by the bolts 33. Of course this 10 supporting member may have its ends curved or stamped out to fit the connector portions where desired and is preferably bifurcated at its ends where it is arranged inside the 15 connector portions so as to pass on opposite sides of the contact portions 45, 46.

Figs. 6 and 7 show still another construction in which integral connector portions 20 may be formed on the strip ends to be directly bolted or clamped together and to be securely connected to the ends of an attaching or supporting member of the buffer, if desired. In this case each of the front strips may be of similar form so as to be bent up in dies in 25 quantity. The front strip 50, for instance, may have the angularly folded or bent portions 52, 53 at its opposite ends, this oblique or angular fold or bend taking place along the lines 57. The other strip 51 may be 30 formed with similar rearwardly and upwardly bent or folded connector portions 52, 53, one of which, 54, is adapted to go behind the cooperating strip end of the other buffer front element which has at its opposite end 35 the rearward strip end 54 so that these two buffer front elements may be made identical in length and shape and have their ends nested together in this way. These end connector portions may be formed with one or 40 more bolt holes or may otherwise be bolted or clamped together; and in many cases it is advantageous to simultaneously clamp or bolt thereto the buffer supporting or attaching members such as the ends 60 of the laterally extending attaching member 61 shown 45 in Fig. 7.

This invention has been described in connection with a number of embodiments, 50 forms, proportions, parts, arrangements, materials, methods of connection and use, to the details of which disclosure the invention is not of course to be limited, since what is claimed as new and what is desired to be secured by Letters Patent is set forth in the 55 appended claims.

I claim:

1. The automobile buffer front comprising 60 a pair of vertically aligned vertically spaced transversely extending buffer front members formed of wide tempered spring steel strip and each having at each end an integral diagonally folded connector portion extending rearward said connector portions having laterally and forwardly extending contact 65 portions formed with bolt holes, connect-

ing bolts clamping said contact portions of the front members together at each end of the buffer front, and a steel strip supporting member having its ends secured to said connector portions. 70

2. The automobile buffer front comprising 75 a pair of vertically aligned vertically spaced transversely extending buffer front members formed of wide steel strip and each having at each end an integral connector portion extending rearward said connector portions having laterally and forwardly extending contact portions connected together at each end of the buffer front, and a steel strip supporting member having its ends secured to 80 said connector portions.

3. The automobile buffer front comprising 85 two vertically aligned vertically spaced transversely extending buffer front members formed of wide steel strip and each having at each end an integral obliquely folded rearwardly bent connector portion and adjacent connected forwardly extending contact portions and buffer supporting members secured to 90 said connector portions.

4. The automobile buffer front comprising 95 two separately formed vertically spaced transversely extending buffer front members formed of vertically wide steel strip and each having at each end an integral obliquely folded rearwardly extending connector portion, said portions having cooperating portions presenting oppositely bevelled rounded loop ends and means connecting said connector portions of the front members together 100 at each end of the buffer front, and means to adapt said buffer front to be supported from the automobile frame.

5. The automobile buffer front comprising 105 separately formed vertically spaced transversely extending buffer front members of wide steel strip having at each end cooperating rearwardly bent connector portions being folded over toward each other to form oppositely bevelled rounded loop ends, and said 110 connector portions being bolted together and to a supporting member adapted to be connected to the automobile frame and support the buffer front therefrom.

6. The automobile buffer front comprising 115 several separately formed vertically spaced transversely extending buffer front members of vertically wide steel strip having at each 120 end cooperating rearwardly folded converging integral connector portions said connector portions presenting oppositely bevelled rounded loop ends adapted to be detachably bolted together, and a rear bar secured at each of its ends to said buffer front and adapted to be attached to the automobile frame to 125 support said buffer.

7. An automobile buffer comprising a plurality of wide thin separately formed resilient metal strip portions constituting an impact element, said strips being arranged in 130

vertical relation to each other and each strip having an integral and connector portion at the lateral end of the element folded angularly to bring the extremities of said folded portions of said connector portions into proximity, said connector portions at the adjacent lateral ends of said strips forming oppositely bevelled rounded loop ends connected to each other to hold said strips in spaced vertical relation.
